(57) **CLAIM**

The ornamental design for a connector for optical fiber cable as shown and described.

DESCRIPTION

FIG. 1 is a front view of a connector for optical fiber cable of our new design;

FIG. 2 is a rear view thereof;

FIG. 3 is a top plan view thereof;

FIG. 4 is a bottom view thereof;

FIG. 5 is a right side view thereof;

FIG. 6 is a left side view thereof;

FIG. 7 is a top perspective view thereof;

FIG. 8 is a bottom perspective view thereof;

FIG. 9 is a cross-sectional view taken along the line 9-9 of the FIG. 1;

FIG. 10 is a cross-sectional view taken along the line 10-10 of the FIG. 1;

FIG. 11 is a cross-sectional view taken along the line 11-11 of the FIG. 1; and,

FIG. 12 is a cross-sectional view taken along the line 12-12 of the FIG. 1.

The broken lines show portions of a connector for optical fiber cable that form no part of the claimed design.

The alternate long and short dash lines are merely the boundary lines between the claimed parts and the non-claimed parts.
